UNITED STATES PATENT OFFICE.

JAMES FRANCIS CROWLEY, JR., OF LARUE, OHIO.

CEMENT-BLOCK MOLD.

1,250,097.

Specification of Letters Patent. Patented Dec. 11, 1917.

Application filed February 21, 1917. Serial No. 150,184.

To all whom it may concern:

Be it known that I, JAMES FRANCIS CROWLEY, Jr., a citizen of the United States, residing at Larue, in the county of Marion 5 and State of Ohio, have invented certain new and useful Improvements in Cement-Block Molds; and I do declare the following to be a full, clear, and exact description of the invention, such as will enable others 10 skilled in the art to which it appertains to make and use the same.

This invention relates to new and useful improvements in molds for manufacturing cement building blocks.

15 The principal object of the invention is to produce a very simply constructed mold formed of a few number of parts which may be quickly assembled or disassembled.

Another object of the invention is to provide 20 a mold of this character by which blocks may be molded by what is known as the "wet process".

With these and many other objects in view, the invention resides in the novel features of construction, combination, and arrangement of parts which will be hereinafter more particularly described and claimed and shown in the drawings wherein:

Figure 1 is a plan view partly in section 30 of a mold constructed in accordance with my invention;

Fig. 2 is a side elevation of the parts shown in Fig. 1;

Fig. 3 is a vertical longitudinal section 35 on the plane of the line 3—3 of Fig. 1;

Fig. 4 is an end view of the mold;

Figs. 5 and 6 are vertical transverse sections on the lines 5—5 and 6—6 of Fig. 1;

Fig. 7 is a plan view of a number of molds 40 showing how the same may be held together;

Fig. 8 is a side elevation partly broken away of a modified form of mold, for use particularly in forming silo building blocks;

Fig. 9 is a section on the line 9—9 of Fig. 8; and

Fig. 10 is a plan view of a block which may be formed in this mold, said block having a face constructed of a slab of stone and a body of cement.

50 Referring more particularly to the several figures of the accompanying drawings, wherein similar reference characters indicate like parts throughout the several views, it will be seen that the invention consists 55 of a mold constructed of a pair of side plates

1, a pair of end plates 2, and a bottom or pallet 3, these several parts being held together in an improved manner.

Each of the side plates 1 is preferably rectangular and of a size corresponding to 60 the size and character of the building block which is to be formed in the mold. In practically all types of building blocks one or more vertical openings are formed through the center, so that when the same are disposed one upon the other to form the wall of the building, there will be a free circulation of air through the blocks. In the present instance provision is made for forming these openings by the cores 4, two of 65 which are made integral with each of the plates 1. Each of these cores is substantially frusto-conical with the small ends thereof extending inwardly toward the other plate when said side plates are disposed in 70 operative position. The cores are connected by an inwardly extending portion 5, which will form a channel in the top and bottom of each block when the same is molded. The inner ends of each of the cores 4 is closed 75 as shown at 6 and provided with a keyhole slot 7, and when the two plates are disposed in operative position with these inner ends of the cores engaging each other, these keyhole slots will be alined. Bolts 8 extend 80 through these slots 7, and when the nuts 9 which are screwed upon their threaded ends are tightened the two side plates will be rigidly held in spaced apart relation. By providing slots 7 of keyhole shape, the plates 85 may be rigidly and quickly separated if bolts having heads smaller than the large portions of the slots are used, since when it is necessary to separate the plates, the nuts 9 may be slightly loosened so as to move the 90 bolts laterally until their heads may pass through said large portions of the slots.

The end plates 2 are also preferably rectangular and of a size to closely fit between the ends of the side plates as shown in the 100 several figures of the drawings. At the top and bottom of each of the end plates and on their opposite side edges are formed the outwardly projecting ears 10 and 11 which are disposed in notches 12 and 13 formed 105 in the upper and lower edges of the side plates 1. In assembling these plates the ears 10 and 11 are placed in their respective notches, and when the bolts and nuts 8 and 9 are tightened, these end plates will be se- 110

curely locked in position so that it will be impossible to disassemble the plates until the nuts 9 are loosened. Each of the end plates is further provided with an inwardly 5 extending portion 14 by which the usual channel in the end of the completed block is formed, the adjacent channels receiving the ordinary binding material to hold the adjacent blocks together. The upper edge 10 of each end plate has an outwardly laterally extending flange 15 formed integrally therewith, the upper edge of said flange being in the plane of the upper edges of the side plates.

15 The bottom or pallet 3 of this improved mold forms the face of the block, and it may be plain or of any other configuration to imitate cut stone and the like. The opposite end edges of this pallet rest upon a pair 20 of spaced apart inwardly extending lugs 16 which project from the lower portion of each end plate 2 as shown in Fig. 3. The opposite ends of the pallet are provided with feet 17 to space the same above the ground 25 so that it may be readily lifted.

In the use of this improved mold, assuming that the same has been assembled, cement in a rather wet condition is poured into the open top of the mold and allowed to settle 30 around the cores 4 or inwardly extending portions 5. This cement must be sufficiently wet to readily flow and entirely fill up the mold without tamping or otherwise pressing the material into shape. Any mold 35 which can be used with the wet process of forming building blocks will form such blocks much more cheaply than those manufactured by the dry process in which it is necessary to use expensive machinery for 40 pressing the material. After the cement has been poured into the mold until it is level with the top edges thereof, the same may be carried to a suitable place to permit it to be dried. Carriage is facilitated by the 45 goosenecked notches 18, one of which is formed in the end of each side plate, it being obvious that a handle of suitable design may be connected with the adjacent notches at each end of the mold.

50 As soon as the cement has set, which occurs within from five to twenty-four hours depending upon the climatic conditions and so forth, the mold is disassembled by loosening the nuts 9 of the bolts 8 and entirely 55 removing the same from both of the cores of each plate, or moving the heads of the bolts until they may be slipped through the large portions of the keyhole slots, and then moving the side plates outwardly away 60 from each other. This causes the disengagement of the ears 10 and 11 from the notches 12 and 13, and readily permits the end plates to be disengaged from the partially hardened block. The parts of the 65 plates are preferably immersed in a solution

of any suitable form of oily compound to coat the same and to prevent the cement from sticking thereto.

In Fig. 7 a number of molds constructed as above described are shown connected together to produce a "battery". These molds are held together by a pair of rods which extend through the openings 7 in the several cores, said rods being provided with nuts on their opposite ends so that all the 75 parts may be tightly clamped together. By this arrangement a number of molds may be poured at one operation, and the whole transported to a suitable drying place. The parts of the molds readily fall apart when 80 the rods are removed.

The blocks which are formed in the molds above described and shown in Figs. 1 to 7 are used for building ordinary houses, stables and the like, or those buildings whose 85 walls are flat. In Figs. 8 and 9 is illustrated a mold used for forming silo blocks or other buildings whose outer faces are curved. In this instance the pallet 3' is curved a sufficient extent, and the other plates are 90 shaped to conform thereto. It is usually necessary in constructing a silo to reinforce the same with a number of bands which surround the completed building at spaced intervals. The bands are also preferably used 95 when the structure is built of cement blocks formed in this mold. However, these bands will be embedded in the blocks themselves, provision being made in the block to receive the same. These bands are disposed in channels formed in the block when the same is cast in the mold, said channels being shaped by the inwardly extending portions 20 on the side plates 1'.

It is well known that the cost of marble, 105 granite, and other expensive stones precludes their use in ordinary buildings. This expense may be greatly lessened by producing a building block having merely the outer face formed of marble or the like. I 110 may construct such blocks in the molds as shown in the accompanying drawings. This is accomplished by providing a thin plate of the desired kind of expensive stone, placing it in the bottom of the mold or the pallet 115 thereof, and then pouring the cement therein. When the material has hardened a building block has been formed which has all the appearance of being a solid block of expensive stone when viewed from the face 120 thereof. In Fig. 10 is shown a building block constructed in this manner, 21 being the plate of marble or the like, which is in effect a veneer, and 22 represents the cement or concrete backing.

Having thus described my invention, what I claim as new is:

1. A collapsible mold of the class described comprising a pair of side plates, a core fixed to the adjacent side of each of 130

said plates, the walls of said cores being tapered inwardly, the smaller end of each core being closed and disposed in engagement with the other, said ends being flat and 5 provided with aligned slots, a fastening element in said slots, end plates connected to the ends of said side plates, and a bottom plate.

2. A collapsible mold of the class described comprising a pair of side plates, a core formed integrally with each of said plates and extending inwardly, means for uniting the inner ends of said cores to hold said plates in rigid spaced apart position, 15 a pair of end plates, and a bottom plate.

3. A collapsible mold of the class described comprising a pair of side plates each having a pair of openings in each end portion, one being adjacent the upper edge and 20 the other the lower edge, a core fixed to the adjacent side of each of said plates and extended inwardly, means for uniting the inner ends of said cores to hold said plates in rigid spaced apart relation, a pair of

end plates, a pair of ears extending from each side edge of each of said end plates and disposed in said openings, and a bottom plate.

4. A collapsible mold of the class described comprising a pair of side plates, a core fixed to the adjacent side of each of said plates, means for uniting the inner ends of said cores to hold said plates in rigid spaced apart relation, a pair of end plates disposed between the ends of said side plates, a pair of spaced lugs on the inner surface of each of said end plates adjacent its bottom edge, and a bottom plate, the same having its opposite ends resting upon said lugs. 40

In testimony whereof I have hereunto set my hand in the presence of two subscribing witnesses.

JAMES FRANCIS CROWLEY, JR.
